EX

SIGN.

W. N. PEAK.

WALL PAPER.

No. 17,016.

Patented Dec. 7, 1886.

UNITED STATES PATENT OFFICE.

WILLIAM N. PEAK, OF BROOKLYN, NEW YORK.

DESIGN FOR WALL-PAPER.

SPECIFICATION forming part of Design No. 17,016, dated December 7, 1886.

Application filed August 20, 1886. Serial No. 211,453. Term of patent 3½ years.

To all whom it may concern:

Be it known that I, WILLIAM N. PEAK, of the city of Brooklyn, in the county of Kings and State of New York, have invented and produced a new and original Design for Wall-Paper, of which the following is a specification.

The nature of my design is fully represented in the accompanying print, to which reference is made.

The design consists, principally, of a griffin-like figure with body *a a*, curved head and neck *b*, feet *c c*, and tail *d*. A double series of blocks or Greek crosses, *e e' e''*, appear at the 15 breast and below the figure, and another series, *e' e''*, appears below and at the rear, and also another series, *f f*, at the back of the fig-

ure. Surrounding the figure and the Greek crosses is a ground, *B*, finished in small stripes. Above the back of the figure is an intermediate 20 stepped figure, *C*, and an isolated Greek cross, *D*, and surrounding the figures and the Greek crosses is a narrow stepped dark border, *g*, and also a corresponding opposite light border, *h*, which gives the outline to the figures, as shown 25 in the accompanying print, and gives a raised effect to the figures.

I claim—

The design for wall-paper, substantially as shown in the accompanying print.

WILLIAM N. PEAK.
